UNITED STATES PATENT OFFICE.

ARCHIE BLAKE, OF NEW ORLEANS, LOUISIANA, ASSIGNOR OF ONE-THIRD TO MRS. REBECCA W. CHANDLER.

SWITCH-OPERATING DEVICE.

1,383,903.

Specification of Letters Patent.

Patented July 5, 1921.

Application filed August 16, 1920. Serial No. 403,710.

To all whom it may concern:

Be it known that I, ARCHIE BLAKE, a citizen of the United States, residing at New Orleans, in the parish of Orleans and State 5 of Louisiana, have invented new and useful Improvements in Switch-Operating Devices, of which the following is a specification.

The present invention has reference to improvements in railway constructions, and is 10 in the nature of an appliance for switch operating mechanism.

The primary object is the production of means in connection with the ordinary switch throwing mechanism, whereby the switch 15 points will be effectively held in hugging relation with respect to the rails, so that liabilities to accidents which frequently occur by the points leaving the rails will be effectively obviated.

20 A further object is the provision of a safety appliance for use in connection with the throwing mechanism of switch points, which can be easily installed and which will be automatic in action.

25 A still further object is the production of mechanism including spring influenced means that act directly on the bridle bar of the switch points to effect either a pushing or pulling action on the bridle bar, in accordance with the switch points that are brought 30 against the rails to insure the retention of said points against said rails.

A still further object is the production of 35 mechanism of this character which shall be of a comparatively simple construction, cheaply manufactured, easily installed, not liable to breakage or disassociation, and which will act automatically in a thoroughly efficient manner.

40 The foregoing, and other objects which will appear as the nature of the invention is better understood, may be accomplished by a construction, combination and operative arrangement of parts, such as is disclosed by 45 the drawings.

In the drawings:—

Figure 1 is a plan view of a portion of a railway system illustrating the application of the improvement between the switch stand 50 and bridle bar for the switch points.

Fig. 2 is a similar view with the top member of the casing of the improvement removed.

Fig. 3 is a similar view but showing the

points thrown to the opposite position from 55 that illustrated in Figs. 1 and 2.

Fig. 4 is a similar view, on an enlarged scale, approximately on the line 4—4 of Fig. 1.

Fig. 5 is a perspective view of the bottom 60 member of the casing.

Fig. 6 is a view of the throw rod and the elements associated therewith.

Fig. 7 is a sectional view approximately on the line 7—7 of Fig. 6. 65

In the drawings the rails for a main line of a railway system are indicated by the numeral 1 and those of a siding by the numeral 2. Between the main and siding rails are the usual switch rails 3 which have their points 70 connected, in the usual manner, by the bridle bar 4.

To one side of the main track is the switch stand 5 provided with the usual vertically disposed shaft operated by the usual angle 75 extension or arm having the pivoted lever 6 that is designed to engage in either of the spaced notches 7 on the extending plate on the top of the stand. The shaft 8, on its lower end is provided with the usual offset 80 finger 9, which, in the present instance, is pivotally connected to the bifurcated end of the operating rod 10 that constitutes one of the elements of the improvement. 85

The operating rod 10, for the major portion of its length is housed in a casing. The casing constitutes a lower section 11 and an upper section 12 that is bolted or otherwise secured on the lower section. The lower section 11 has at its outer end a conical extension 13, the inner portion of the said extension being formed with a round depression 14 that registers with the bore of the sections, and the extreme end of the extension 13 is bifurcated, as at 15, receiving therein the end 90 of the bridle bar to which it is pivotally connected. 95

The bore of the sections that constitute the casing is centrally enlarged providing shoulders 16 and 17 at the ends thereof. The 100 depression is of a material length, and the inner shoulder 16 thereof is designed to be contacted by a disklike collar 18 on the reduced inner portion 19 of the operating rod 10, the sliding of the collar being limited 105 by the contact thereof with the shoulder provided between the rod proper and the reduced extension thereof. This collar 18 is

contacted by a helical spring 20 that is received on the reduced end of the operating rod, the said spring contacting with the flanged end 21 of a sleeve member 22 that 5 is loose on the reduced end of the rod 10. The rod 10 has its end, on which the sleeve is received threaded and has secured thereon a nut 23. The numeral 24 designates a locking element which is preferably in the nature 10 of a cotter pin that passes transversely through the end of the rod 10, and contacts with the nut to hold the nut against unscrewing. The flange 21 of the sleeve 22 contacts with the shoulder 17 in the cylindrical 15 casing.

The lower section 11 of the casing preferably has its edges provided with outstanding ears 25, and the upper section 12 has its edges provided with similar ears 26, 20 which rest on the ears 25. Through these ears are passed the securing elements which are preferably in the nature of bolts 27 that are engaged by nuts 28.

The section 12 of the casing, adjacent to 25 the ends thereof has oil-openings 29 therethrough which are normally closed by caps 30 that are pivotally supported on the said upper casing section. By this arrangement it will be noted that a lubricant may be at 30 all times fed into the casing, so that the rod will freely slide therethrough.

The sleeve and the reduced end of the operating rod 10 are of a size to be received in the bore of the casing extension 13. 35 When the switch points are thrown to the position illustrated in Figs. 1 and 2, the rod 10 will have been moved toward the rails, compressing the spring between the collar 18 and the flange 21 of the sleeve 22, the end 40 of the rod having been forced into the bore at the closed end of the casing, so that the collar 18 is brought out of contact with the inner shoulder in the casing. This will effect the holding of the switch point tightly 45 against the outer rail, to permit of the train traveling over the main track on to the siding, when the train travels in the direction of the arrow B in Figs. 1 and 3. However, should a train travel in the direction 50 of the arrow A, the spring will yield when

the flanges of the wheels of the rolling stock pass between the main rail and switch point. When the points are thrown to open the main line the spring will be compressed between the collar and the flange 21, the said 55 collar having been forced against the inner shoulder in the casing, so that the inner switch point is held tightly against the inner main rail. Thus a train traveling in the direction of the arrow B in Fig. 1 will pass 60 directly on the main line, but should a train travel from the siding in the direction of the arrow A the flanges of the car wheels contacting with the inner face of the switch point that hugs the rail will move the same 65 away from the said rail. The spring is of sufficient strength to prevent the accidental throwing of the switch, and it is thought that the foregoing description, when taken in connection with the drawings will fully 70 set forth the simplicity of the construction and the advantages thereof without further detail description.

Having thus described the invention, what I claim is:—

In combination with the main and siding rails of a railway system, switch points therebetween, a bridle bar connecting the switch points, and a switch stand having switch mechanism associated therewith and locking means therefor; of a two-part casing having a closed end which is pivotally connected to the bridle bar, removable means connecting the sections of the casing, and the said casing having a centrally depressed 85 portion therein, an operating rod slidable through the open end of the casing and pivotally connected with the throw mechanism of the switch stand, a collar on the reduced end of the operating rod, a flanged sleeve 90 on the extreme reduced end of the operating rod, means for holding the sleeve against outward movement on the operating rod, and a helical spring surrounding the operating rod and exerting a tension against the 95 flange of the sleeve and the collar, all as and for the purpose set forth.

In testimony whereof I affix my signature.

ARCHIE BLAKE.
